UNITED STATES PATENT OFFICE.

DANIEL KOPS, OF NEW YORK, N. Y.

APPAREL-CORSET.

1,233,251.

Specification of Letters Patent. Patented July 10, 1917.

Application filed March 24, 1917. Serial No. 157,075.

To all whom it may concern:

Be it known that I, DANIEL KOPS, a citizen of the United States, residing in the borough of Manhattan, city, county, and State of New York, have invented an Improvement in Apparel-Corsets, of which the following is a specification.

My present invention relates to an apparel corset and more particularly to that type of corsets in which devices are employed for properly supporting the abdomen of the wearer. In Letters Patent, No. 1,127,024, granted February 2, 1915, as well as in Letters Patent, No. 1,152,109, granted August 21, 1915, corset garments are shown and described in which there are employed tension devices adjustable to position to simultaneously exert an inward and an upward tension on the lower portions of the front steels to create a pressure in corresponding directions against the abdomen of the wearer to properly support the same. In the garments, as illustrated in these patents, the devices employed for this purpose comprise tension straps which are secured at distant ends to the body of the garment and at their adjacent ends to the lower front portions of the garment at the lower ends of the front steels, the tension straps being divided and fitted with means making them adjustable to exert an inward and upward tension on the lower front portion of the garment which acts in this manner independently of the overlying skirts. These garments, however, are made in halves and laced at the rear and connected by clasps at the front.

To properly adjust the ordinary form of back lace corset to the body of the wearer, the laces at the back must be loosened when the garment is removed and drawn up and tied again when the garment is replaced on the body of the wearer, as otherwise the proper adjustment of the garment to position cannot possibly be obtained.

The object of my present invention is to apply similar devices for accomplishing the same purpose in a closed back and front lace corset garment in which consequently the entire adjustment of the garment to position on the body of the wearer is effected in the front of the corset.

In carrying out my present invention the usual halves of the corset garment are preferably connected permanently at the rear and the structure is such that the garment is

adjusted to position at the front thereof where laces for this purpose are provided on one or both sides of the front steels which are adapted to be hooked together in the usual manner. At the front portion of the garment I employ tension straps which may coact with the lower front portions of the garment directly or indirectly or independently thereof to produce a simultaneous inward and upward pressure against the abdomen to properly support the same. These tension straps are preferably placed on the inner side of the garment and are adjustable from the outer side thereof after the same is in position on the body of the wearer. When the tension straps are so constructed as to coact directly with the lower front portions of the garment, the forward ends thereof are connected adjacent the lower portions of the front steels and extend rearwardly whereby adjustable devices they are attached to the garment adjacent to or forward of the hip sections for performing the function stated. When coacting indirectly with the lower front portions of the garment, these tension straps may be provided with a suitable pad member overlying the lower front portion of the garment and secured to one another, and free from the garment extend rearwardly adjacent the hip section provided with adjustable devices which are the same as those in the other forms of the invention, whereas when acting independently of the lower front portion of the garment these tension straps with the pad underlie the garment and bear directly against the body of the wearer.

In the preferred form of my invention the steels are placed so as to be in a central position when the garment is on the body of the wearer and the laces employed for adjusting the garment on the body are placed adjacent the steels, on either side thereof. The laces connect the front steel section with the body of the garment, and the forward ends of the adjustable tension straps are also connected to the front steel sections so that the tension straps not only produce the simultaneous inward and upward pressure against the abdomen, but also, acting through a front steel section tend to effect a downward tension throughout the front portion of the garment to keep the parts in place and produce a uniformly smooth effect.

The improved corset made in accordance

with my present invention will be herein-after more particularly described in connection with the accompanying drawings in which:

5 Fig. 1 is a front perspective view showing the application of a form of the apparel corset made in accordance with my present invention.

10 Fig. 2 is a rear perspective view of the same.

15 Fig. 3 is an enlarged front elevation of the form of corset shown in Figs. 1 and 2.

Fig. 3^a is a cross section on line 3—3 Fig. 3.

20 Fig. 4 is a view similar to Fig. 1 illustrating the application of another form of the corset made in accordance with this invention.

25 Fig. 5 is an enlarged elevation of the front portion of the right hand side of the corset garment shown in Fig. 4.

30 Fig. 6 is a view similar to Fig. 5, showing another form of the invention illustrated in Fig. 4.

35 Fig. 7 is a cross section on line 7—7.

40 Fig. 8 is a view similar to Figs. 5 and 6 showing still another form of the invention.

45 Fig. 9 is a front elevation of the corset garment illustrating another modification of the present invention.

50 Fig. 10 is an enlarged front elevation of the lower portion of the corset shown in Fig. 9.

55 Referring to the drawing and particularly to Figs. 1, 2 and 3, it will be seen that in carrying out my present invention the body of the garment is made in one part. In these figures the body of the corset is indicated at 12 and at the rear instead of being made to be connected and adjusted by the usual lacing devices, the parts are permanently connected by a strip of fabric 13. This strip of fabric may be made of any construction but is preferably made with relatively large interstices for ventilating purposes. The body of the garment is provided with depending skirts indicated at 14 and at the rear, and as particularly illustrated in Fig. 2, the skirt members at the rear may be connected by a strip of elastic fabric 15 to permit of the necessary yielding movement when the wearer of the garment is in a seated position.

60 The corset made in accordance with this invention as heretofore intimated, is a closed back and front laced garment. In this corset however, the lacing is preferably placed at the side of the front central line and the front steels 16 and 17 provided with clasps 18 adapted to be connected in the usual manner and to assume a front central position as is customary in corset garments when on the body of the wearer. In the form of the invention shown in these figures the front por-

tion of the left skirt 19 is undivided and is connected to the front steel section 21 along a line of sewing 20 which is appreciably above the lower end of the front steel 16 so that the front of the skirt overlies the lower portion of this front steel. I also employ a tension strap 22 which at one end is connected to a front steel section 21 along a line of sewing 23 or otherwise so as to lie beneath the front portion 19 of the left skirt. This tension strap 22 extends rearwardly and at its opposite end is provided with a series of eyelets 24. In this side of the garment there is also an anchor strap 25 secured along one edge in the garment at approximately the hip section or slightly forward thereof and extending forwardly, and provided at its opposite edge with a series of eyelets 26. A lace 27 is passed through the eyelets 24 and 26 and also through eyelets 28 in the front skirt section 19 and adapted to be drawn outwardly and tied in a knot 29 to adjust the tension strap 22 and anchor strap 25 to position for use.

65 The front steel 17 is fixed in a steel section 30 on the right side of the garment at the front thereof, and this is provided with a lacing strip 31 in which there are eyelets 32. The front steel section 30 is also provided with a tongue 33 for a purpose hereinafter indicated. The edge of the body of the garment lying adjacent the steel 17 is also provided with eyelets 34 corresponding in number and located similarly to the eyelets 32, and a lace 35 is passed through the eyelets 32 and 34 to draw the parts of the garment together at the front thereof and so adjust the same to position on the body of the wearer. In so adjusting the garment to position as will be understood, the tongue 33 lies beneath the lacing devices and connects the adjacent edges of the garment in order that the flesh may not protrude between these edges and the lacing devices. It will be understood that the tongue is sufficiently wide to permit the garment to open the required extent at the lacing edges to be placed and adjusted to position on the body of the wearer.

70 The front portion of the skirt on the right hand side of this garment is divided along the line indicated at 36. One section 37 of this divided skirt is secured to the front steel section 30 along a line of sewing 38 or otherwise so as to be similar in all respects to the location and manner of attaching the front section 19 of the skirt on the opposite side of the garment to the front steel section 21. The other skirt section 39 on the right side of the garment is attached to and depends from the body of the garment adjacent the lower front lacing section thereof and at their lower ends the sections 37 and 39 of this divided skirt are suitably secured together.

In the right hand side of the garment I also employ a tension strap 40 similar to the tension strap 22 and the tension strap 40 is secured along one edge to the front steel section 30 in a line of sewing 41 or otherwise, and for a portion of its length along its upper edge this tension strap 40 is also connected to the lower edge of the tongue 33 so that by the pressure exerted on the tension strap the tongue is at all times maintained in position during the use of the garment as shown in Fig. 3^a. In the right hand side of the garment there is an anchor strap 43 connected at one edge adjacent the hip section of the garment and extending forwardly. On its opposite edge the anchor strap 43 is provided with a series of eyelets 44 through which and through the eyelets 42 a lace 45 is passed, and which extending through eyelets 46 in the skirt of the garment is adapted to be drawn outwardly and tied in a knot 47 to adjust the tension strap 40 and anchor strap 43 in position, it being understood that these tension and anchor straps coact with the lower front portions of the steels to simultaneously exert an inward and an upward pressure against the body of the wearer. Also, as indicated in these figures of the drawing, the skirt sections may be supplied with suitable hose supporters 48 and at a point slightly below the attachment to the front steel sections, the front skirt sections may be provided with a hook 49 and an eye 50 to connect the adjacent edges of the skirt sections one to the other.

By reference to Figs. 4 and 5 it will be seen that the corset made in accordance with this invention may be so constructed that the lacing devices for adjusting the garment to position on the body of the wearer may be placed on both sides of the front steels which as in the construction shown in Figs. 1, 2 and 3 are adapted to assume the front central position on the body. In other words, both front portions of the garment are similarly constructed and for this reason in Fig. 5 I have illustrated only the right hand side of the garment. In this structure the front steel 17 is fixed in a front steel section having a lacing strip 51 in which there is a series of eyelets 52. Laces 53 are passed through these eyelets 52 as well as eyelets 54 placed in the adjacent edge 55 of the body of the garment. As illustrated in the drawing, the eyelets 52 and 54 are placed in staggered positions although as will be understood, the invention is not limited to so placing the eyelets. The front steel section in which the front steel 17 is located is also provided with a tongue 56 adapted to span the edges of the garment in a manner similar and for the same purpose as the corresponding member employed in the preferred form of the inven-

tion as hereinbefore described, but as shown in Fig. 7 the tongue 56 is not connected to the body of the corset.

In this form of the invention, as in the preferred form hereinbefore described, I employ a tension strap 57 which at one end is suitably connected to the lower portion of the front steel section, and along a part of its upper edge to the lower edge of the tongue member 56. This tension strap 57 extends rearwardly and at the inner edge is provided with a series of eyelets 58. In this form of the invention I also employ anchor straps and the one on the right hand side of the garment is indicated at 59. This anchor strap is secured at one edge adjacent the hip section or slightly forward thereof, and at its opposite edge is provided with a series of eyelets 60. A lace 61 is threaded through the eyelets 58 and 60 and also passed through eyelets 62 in the skirt of the garment so that the anchor strap and tension strap may be adjusted to position by drawing up the lace and tying the same in a knot 63 on the exterior of the skirt. In this form of the invention, also the lower front portion of the skirt as indicated at 64 is tapered or inclined so as to overlap a portion of the front steel section, and as is customary may be provided with a hose supporter 65 at the lower front edge.

In Fig. 6 the structure is similar in all respects to that shown in Fig. 5 with the exception that the lower forward edge of the skirt section as indicated at 66 is continued straight downwardly from the forward edge of the body of the garment. In Fig. 7 the tongue member 56 as employed in these and other forms of the invention is illustrated in cross section.

Similarly Fig. 8 illustrates a form of the invention which is the same as that shown in Fig. 5 with the exception that the front skirt section is made to be adjustably attached to the lower portion of the front steel section. This as illustrated is accomplished by the use of a hook 67 fixed in the forward edge of the skirt section and adapted to engage with either one of a series of eyes 68 provided therefor in the front steel section and the adjacent part of the tension strap.

In Figs. 9 and 10 I have illustrated a still further modification of the invention in which the front steel sections are adapted to lie at one side of the front central line of the body and the lacing devices to assume a central position when the garment is on the body of the wearer. In this form of the invention I have also illustrated a modified form of the uplifting devices for properly supporting the abdomen of the wearer. Referring to these figures the front steels are indicated at 70 and 71 respectively, and as customary are provided with stud and socket

devices 71 and 72 by which the steel sections are connected when in use. The steel section in which the front steel 69 is secured is permanently attached to the front edge of the right hand side of the garment, whereas the steel section in which the front steel 70 is secured is provided with a lacing strip 73 in which there are a series of eyelets 74. The front edge of the left side of the body of the garment is provided with a lacing strip 75 in which there are eyelets 75'. A lace 76 is passed through the eyelets 74 and 75' connecting the parts of the garment and adjusting the same to position on the body of the wearer.

In the right side of this garment I also employ a tension strap 77. As illustrated this is preferably connected, as indicated at 78, with a lower portion of the front steel 20 section in which the front steel 69 is secured, the connection being made only adjacent the upper forward edge of the tension strap. At its opposite or rearward edge this tension strap is provided with a lacing strip 79 25 in which there are eyelets 80. Adjacent the right hip section of the garment or slightly forward thereof one edge of an anchor strap 81 is secured. On the opposite edge of this anchor strap there are eyelets 82 corresponding in number with the eyelets 80 on the tension strap 77. A lace 83 is passed through the eyelets 80 and 82 and also through eyelets 84 in the skirt of the garment and adapted to be drawn up exteriorly of the skirt to 30 adjust the tension strap to position in use. In the left hand side of the garment I also employ a tension strap 85. This is attached to the body of the garment as indicated at 86. The upper edge of the forward 35 part of the tension strap is the only portion thereof which is so connected. At its inner end there is a lacing strip 87 secured to the tension strap 85, and in the lacing strip 87 there is a series of eyelets 88. In this side 40 of the garment there is also an anchor strap 89 similar to the anchor strap 81, and consequently provided with a series of eyelets 90. A lace 91 is passed through the eyelets 88 and 90 and also through eyelets 92 in the 45 skirt of the garment so that the lace 91 may be drawn up exteriorly of the skirt and suitably tied in order to adjust the tension strap to position in use. Connected to the forward edge of the tension strap 85 is one edge 50 of a pad member 93. This member may be suitably boned or stiffened by stays indicated at 94 and is connected to the tension strap 85 as hereinbefore stated, along a line of sewing indicated at 95 or otherwise. At its 55 opposite edge this pad member is provided with eyes 96 adapted to be engaged by hooks 97 secured to the forward edge of the tension strap 77 so as to connect these parts together. As indicated in Figs. 9 and 10, the 60 lower front portions of the skirt members 65

may be cut away as indicated at 98 and provided with suitable hose supporters 99.

In the structure hereinbefore last described, and as illustrated in Figs. 9 and 10, the uplifting tension devices comprising the tension straps 77, 85, the pad member 93, and the lacing devices by which they are adjusted to position, are entirely on the inside of the garment and may be connected thereto as described or entirely free therefrom without departing from the nature and spirit of my invention, and also as will be apparent, a portion of these devices, namely the tension straps and the laces by which they are adjusted to position, may be on the inner side of the garment and the pad member placed on the outer side thereof so as to contact directly with the lower front portions of the steel sections in performing their functions of properly supporting the abdomen of the wearer.

I claim as my invention:

1. An apparel corset comprising a body member, front steels adapted to be connected to one another, lacing devices for connecting one front steel to its portion of the body member, and adjusting devices on the inner side of the garment and in the lower front portion thereof for effecting an inward and an upward pressure 95 against the body of the wearer.

2. An apparel corset comprising a body member, front steels adapted to be connected to one another, lacing devices for connecting one front steel to its portion of the body member, and extending downwardly and terminating a material distance above the lower ends of the front steels, and adjusting devices on the inner side of the garment and extending below the lacing devices for effecting an inward and an upward pressure against the body of the wearer.

3. An apparel corset comprising a closed-back body member, front steels adapted to 110 be connected to one another, lacing devices for connecting one front steel to its portion of the body member, a tongue connected to the body member and underlying the said lacing devices, and adjusting devices on the inner side of the garment and in the lower front portion thereof for effecting an inward and an upward pressure against the body of the wearer.

4. An apparel corset comprising a closed-back member, front steels adapted to be connected to one another, lacing devices for connecting one front steel to its portion of the body member, and extending downwardly and terminating a material distance 125 above the lower ends of the front steels, skirt members depending from the body member and at their front ends loose therefrom for an appreciable distance above the lower ends of the front steels, and adjust- 130

ing devices underlying the said skirt members in the lower front portion of the garment for effecting an inward and an upward pressure against the body of the 5 wearer.

5. An apparel corset comprising a closed back body member, a front steel connected to one end of the body member, an undivided skirt depending from this end of the 10 body member at the front thereof and loose therefrom for an appreciable distance above the lower end of the front steel, a second front steel, a divided skirt depending from the other end of the body member, and tension devices under- 15 lying the front portions of the skirt members and extending below the said lacing devices for simultaneously effecting an inward and an upward pressure against the body of the wearer.
5. 6. An apparel corset comprising a body member, front steels adapted to be connected to one another, lacing devices for connecting one front steel to its portion of the body member, and tension devices under- 20 lying the body member in the lower front portion thereof and adjustable from the exterior of the garment for effecting an inward and an upward pressure against the body of the wearer.
- 30 7. An apparel corset comprising a body member, front steels adapted to be connected to one another, lacing devices for connecting one front steel to its portion of the body member and extending down- 35 wardly and terminating a material distance above the lower ends of the front steels, and tension devices on the inner side of the garment extending below the said lacing devices and adjustable exteriorly of the 40 garment for effecting an inward and an upward pressure against the body of the wearer.

8. An apparel corset comprising a closed back body member, a front steel connected to one end of the body member, a skirt de- 50 pending from the body member and loose therefrom at the front an appreciable distance above the lower end of said front steel, a second front steel, a divided skirt member at the other end of the body mem- 55 ber and loose therefrom at the front an appreciable distance above the lower end of the second front steel, lacing devices for connecting the said second front steel to its portion of the body member, and tension 60 devices underlying the said skirt members in the front of the garment and adjustable from the exterior thereof for simultaneously effecting an inward and an upward pressure against the body of the wearer. 65

9. An apparel corset comprising a body member, front steels adapted to be connected to one another, lacing devices for connecting one front steel to its portion of the body member extending downwardly 70 and terminating a material distance above the lower ends of the front steels, and skirt members depending from the body member and at their front portions loose from the front steels for an appreciable 75 distance above the lower ends thereof.

10. An apparel corset comprising a closed back body member, a front steel connected to one end of the body member, an undivided skirt depending from this end of the 80 body member at the front thereof and loose therefrom for an appreciable distance above the lower end of said front steel, a second front steel, a divided skirt depending from the other end of the body member and loose 85 therefrom for an appreciable distance above the lower end of the second front steel, and lacing devices for connecting said second front steel to its portion of the body member and extending downwardly and terminating a material distance above the lower 90 end of the said second front steel.

Signed by me this 21st day of March, 1917.
DANIEL KOPS.
